UNITED STATES PATENT OFFICE.

BENJAMIN P. MCKINLEY, OF NEW YORK, N. Y., ASSIGNOR TO HEMCO ELECTRIC MANUFACTURING COMPANY, INC., OF LONG ISLAND CITY, NEW YORK; A CORPORATION OF NEW YORK.

RADIO TUNING DIAL AND MEANS OF MOUNTING THE SAME.

Application filed July 30, 1924. Serial No. 729,044.

This invention relates to index dials for use in connection with tuning condensers of radio receiving apparatus, and it is an object of the invention to provide an improved 5 constructed and arranged dial of this character whereby it may be readily manipulated by the hand and fingers to facilitate the effecting of fine adjustments of tuning condensers.

10 Index tuning dials for this purpose are made of brittle material and are fixed to a shaft element of a rotor member of the condenser, as by a set screw carried by or threaded into the material of the dial and 15 adapted to co-operate with the condenser shaft when mounted thereon to secure the dial in position on said shaft. However, due to the brittleness of the material of the dials great difficulty is experienced in threading 20 the opening for the set screw. It is the usual practice in mounting an element of such material upon an element by means of a set screw to embed a threaded member, which is adapted for the engagement of a set 25 screw, in the material as it is molded. However, due to the construction and arrangement of index dials for radio tuning condensers this is not possible and therefore necessitates the arranging of the threaded 30 member for the set screws in the dials after they are molded.

It is an object of the present invention to overcome the above disadvantages and provide means for the engagement of a set screw 35 and arrange the dial so that said means through the binding action of the screw upon the shaft of the tuning condenser will co-operate with the dial to lock it on said shaft.

In the drawing accompanying and forming 40 a part of this specification, Figure 1 is a front elevation of a dial for radio tuning condenser or the like constructed and arranged in accordance with the present invention.

45 Figure 2 is a bottom view.

Figure 3 is a cross sectional view taken on the line 3—3 of Figures 1 and 2 looking in the direction of the arrows.

50 Figure 4 is a cross sectional view taken on the line 4—4 of Figure 2 looking in the direction of the arrows; and

Figure 5 is a plan view on an enlarged scale of a disk portion of the dial to particularly show the construction and arrangement

of beads and knurls formed on the face of 55 the disk portion and periphery of the knob.

Similar characters of reference designate like parts throughout the different views of the drawing.

The embodiment of the invention illustrated in the drawing comprises a disk portion 6 having a hollow knob 7 axially thereof and closed at the outer end, said knob being arranged with an inwardly extending axial hub 8 with a bore 9 extending thereinto from the inner end for the engagement of a shaft 60 to mount the dial thereon, said shaft consisting of a part of the rotor of a tuning condenser of radio receiving apparatus. The hub 8 is of a length to extend beyond the inner surface 11 of the peripheral portion of the disk to bear against the wall of an enclosing casing for radio receiving apparatus and maintain the disk away from such wall. The disk is arranged with graduations or calibrations 12 thereon adjacent the periphery, said graduations extending substantially 70 around one-half of the circumference of the disk, there being one hundred divisions and numbered in multiples of ten from zero to 75 one hundred.

To facilitate the rotation of the disk and procure fine adjustments of the tuning condenser the knob and disk are arranged with beads 13 equidistantly spaced around the 85 knob and extending longitudinally thereof and continuing radially outward on the disk to adjacent the scale 12 with the portions of the beads tapering slightly outward. Interposed between each pair of beads is a series 90 of knurls 14 extending in parallel relation to the beads with the knurls extending radially of the disk tapering outward from the juncture of the disk with the knob as clearly shown in Figures 1 and 5. By this arrangement a firm grasp may be had on the knob and assure rotation thereof by the slightest movement of the hand or fingers, or the tips of the fingers may be pressed upon the 95 knurls between the beads of the disk and the disk rotatably adjusted with equal facility.

To reinforce the disk portion of the dial, the undersurface is provided with substantially equidistantly spaced ribs 15 extending from a point adjacent to where the knob extends 100 from the disk to a circumferentially flattened portion 16, with ribs 17 of shorter length 105 interposed relative to the ribs 15.

As stated dials for this purpose are made of a brittle material, such as bakelite, redmonal or condensite by molding under pressure and must be so arranged that portions of the dies may be withdrawn therefrom and the article withdrawn from other portions of the dies. Great difficulties has been experienced in securely mounting said dials upon the shafts of tuning condensers, since they must be securely fastened thereon and at the same time be readily releasable therefrom for making repairs or otherwise, and for which purpose a set screw is utilized. Owing to the brittleness of the material the provision of a threaded bore in which to mount the set screw is a tedious operation. To obviate this one of a series of ribs 18 extending between the hub 8 and wall of the knob 7 is arranged with a double wall forming a recess between said walls, as clearly shown in dotted lines at 19 in Figure 3, with a portion thereof laterally enlarged by recessing opposite wall portions of said recess, as at 20, to form a seat and abutment for a nut 21, a perforation 22 through the wall of the hub communicating with said nut seat and the bore in the hub, and there being arranged a perforation 23 in the wall of the knob in line with the hub perforation. To mount and lock the dial upon the shaft 10 the nut is inserted into its seat, and the threaded member, such as a headless set screw 24, is passed through the knob perforation 23 and threaded into the nut so that it will project partly into the hub perforation 22. This is done before the dial is placed upon the shaft. After the dial is mounted upon the shaft it is locked thereto by entering a screwdriver through the knob perforation 23 to engage the slot in the end of the screw and by rotating the screw the end will abut against the shaft while the nut will be backed up or abutted against the shoulders formed by the lateral enlargements of the recess 19 to form the nut seat thereby firmly securing the dial to the shaft.

Tuning condensers usually comprise a series of segmental plates fixed in axial spaced relation and a shaft mounted axially of said plates carrying complementary plates in interposed relation to the fixed plates and adapted to be variably positioned by the shaft in relation to the fixed plates. It is essential that the dial be fixed upon the condenser shaft in predetermined position so

that as the indices in connection with the scale on the dial are brought in register with an index on the casing it will properly indicate the position of the adjustment of the condenser. For this purpose the double walled rib carrying the dial locking means is arranged at substantially eighty degrees in advance of the zero indice of the dial.

To further facilitate the rotating of the dial to obtain relatively fine adjustment of the same the peripheral portion of the face of the dial diametrically opposite to that on which the graduations 12 are arranged is also circumferentially knurled, the knurls extending radially across said portion, as shown at 25. By pressing the tips of the fingers against said knurls 25 and the thumb bearing on the knurls 14 extending longitudinally of the knob and continuing outward on the disk a very fine and ready adjustment of the dial may be obtained, and thereby obviating the necessity of utilizing a vernier adjusting device as now is the case.

Having thus described my invention I claim:

In a dial connection for radio tuning condensers, a disk having an integral axial hollow knob closed at the outer end arranged with an integral hub extending axially inward from the closed end of the knob and in spaced relation to the peripheral wall of the knob, said hub having a bore; ribs extending radially between and merging with the hub and wall of the knob, one of said ribs being arranged with a radial recess opening outward to the end of the hub and enlarged laterally in the direction of the axis of the hub at the juncture of the rib with the hub, the wall of the hub having a perforation communicating with said enlarged portion of the recess; a nut in the enlargement; a threaded member in the recess having threaded engagement with the nut in the recess enlargement; and a shaft in the hub bore adapted to be engaged by said threaded member, and the wall of the knob having a perforation in line with the recess and perforation in the hub for the passage of an implement to manipulate the threaded member.

Signed at New York city in the county of New York and State of New York this 18th day of July A. D. 1924.

BENJAMIN P. MCKINLEY.
